(57) **CLAIM**

The ornamental design for an electronic gaming table with a shared display, as shown and described.

DESCRIPTION

FIG. 1 is a top-front-side perspective view of an electronic gaming table with a shared display showing our new design
FIG. 2 is front/rear view thereof;

FIG. 3 is a right/left side view thereof; and,

FIG. 4 is a top/front/right side perspective view thereof.
The broken lines in the figures show portions of an electronic gaming table and form no part of the design.

1 Claim, 3 Drawing Sheets

FIG. 2

FIG. 3

FIG. 4
